UNITED STATES PATENT OFFICE.

CHRISTIAN GLEERUP-MÖLLER, OF SOLYST, HORSENS, DENMARK.

ADVERTISING APPARATUS.

Application filed March 29, 1924. Serial No. 702,927.

To all whom it may concern:

Be it known that I, CHRISTIAN GLEERUP-MÖLLER, a subject of the King of Denmark, and resident of Solyst, Horsens, Denmark, have invented a new and useful Improved Advertising Apparatus, of which the following is a specification.

This invention relates to an advertising apparatus showing the advertisements on the circumferential wall of a column or drum which is polygonal in horizontal section and the flat parallel wall faces of which consist of semi-transparent mirrors, behind which are superposed compartments containing each a certain article of manufacture which becomes visible when the respective compartment is illuminated interiorly so that the mirror surface disappears.

The advertising column or drum is supported on a stationary base on which it can be rotated by means of a motor housed within that base. The high number of revolutions of the motor is suitably reduced by means of a gearing, by the intermediary of which three or more grooved rollers are rotated, the grooves of which receive a ring connected with the advertising column. The rollers serve, thus, for carrying the column, as well as for rotating it. The ring supported in the roller grooves is provided with projections forming contacts and co-operating with stationary contacts for closing the circuits of the lamps housed in the compartments, the arrangement being such, that the lamps are switched on in such a succession that all compartments are illuminated in a certain order and, therefore, all articles of manufacture contained therein are shown.

The invention is illustrated, by way of example, in the accompanying drawings, in which Figure 1 is a side-view of the advertising apparatus, partly in vertical section; Figure 2 is a horizontal section in the plane A—B of Figure 1; Figure 3 is a horizontal section in the plane C—D of Figure 1.

In Figure 1 *a* is the advertising column, the interior of which is divided into parallel vertical rows of superposed compartments *b*, *b*¹, *b*², *b*³ . . . The superposed compartments are separated from one another by horizontal partition walls *d*, *d*¹, *d*², *d*³ . . . and their rear walls are formed by a common cylinder *c*. The column shown in the drawings by way of example is octagonal, but I wish it to be understood, that it may be hexagonal or quadrangular or triangular,

etc., etc., and also the number of the superposed compartments may be chosen as desired or required.

The wall parts or faces of the drum consist of semi-transparent mirrors *e*, *e*¹, *e*², *e*³ . . . which, thus, close the compartments at their front side. *f* is a kind of cornice of the column, and *g* is a bottom ring or inner flange, by the intermediary of which the column is affixed to a ring *h* of angular section, the horizontal part being connected with said ring and the vertical part engaging the grooves of grooved rollers *k*, *k*¹, *k*² affixed to shafts *l*, *l*¹, *l*², supported in bearings *m* and *n*, *m*¹ and *n*¹, and *m*² and *n*². At the inner ends of said shafts are bevel-wheels *o*, *o*¹, *o*² which mesh with a common bevel-wheel *p* secured to a central vertical shaft *q* driven by an electromotor *u* by the intermediary of a gearing consisting of a worm and worm-wheel *t*, a shaft *s*, a pinion *r*¹ and a large-cog-wheel *r* which is affixed to the shaft *q*. The whole arrangement and combination of parts above-described is carried by a base plate *v*, and the gearing is besides covered by an annular lining *w* extending from the rim of the base plate *v* to the lower rim of the drum *a*.

On the outer surface of the vertical part of the ring *i* are projections *x*, *x*¹, *x*² . . . which are arranged either only at a certain portion or at certain portions of said ring, or extend around the circumference thereof. These projections form contacts which co-operate with a stationary contact *y* (Figure 1) or with a plurality of such contacts, as *y*, *y*¹, *y*², *y*³ . . . *y*ⁿ, Figure 3. The number of the rotatory contacts depends on the number of the compartments to be illuminated successively, or on the number of the lamps respectively which are to be switched on, and the number of the stationary counter-contacts depends on the number of the compartments which are to be illuminated at a time. *z*, *z*¹, *z*², *z*³ are the electric incandescent lamps shown in Figure 1; each lamp is arranged in the upper part of the respective compartment, preferably at the ceiling thereof, and in front of each lamp is an opaque screen *a*, *a*¹, *a*², *a*³ preventing the eyes of the lookers-on from being dazzled by the light of the lamp. Each screen may bear an inscription having reference to the article shown in the respective compartment. The return wires from the individual lamps, which are conducted downwards along the

inner surface of the cylinder c , are combined, finally, to form a cable which is passed through a central bore of the shaft q and terminates at a contact member rotating together with this shaft. There is also, of course, provided for it a stationary counter-contact connected up to the net or any other suitable circuit, or source of electricity respectively.

10 The manner of operation of this advertising apparatus is as follows:

The polygonal drum a is rotated slowly and incessantly by the motor u so that the mirrors $e, e^1, e^2 \dots$ rotate correspondingly

15 and each looker-on sees himself and the surroundings under constantly changing angles.

This state lasts as long as no lamp is switched on, but as the contacts x and $y \dots$ close successively the circuits of the lamps

20 $z, z^1, z^2 \dots$ either singly or in certain groups, the respective lamps are caused to light up whereby the compartments pertaining to the respective lamps are illuminated, in conse-

25 quence of which the respective semi-transparent parent mirrors become practically wholly transparent so that the articles contained in the respective compartments become visible. In this way all articles are successively ex-

30 posed to view, without any necessity for a looker-on to change his place.

The number of revolutions of the motor is greatly reduced by the gearing described, especially by the worm-wheel gearing t , the pinion r^1 , and the cog-wheel r , and the drum

35 is, therefore, rotated only so slowly that every article can be fully examined. The rotatory motion transmitted to the shaft q by the cog-wheel r is transmitted further by the bevel-wheels p and o , the shafts $l, l^1,$

40 $l^2, l^3 \dots$ and the rolls $k, k^1, k^2 \dots$ to the ring i so that the entire drum with its contents is rotated correspondingly slowly. Now, of course, also the contacts $x, x^1, x^2 \dots$ are moved round and contact successively with

45 the stationary contacts $y, y^1, y^2 \dots$ as already described, closing then the respective lamp circuits.

The main advantages obtainable by the new construction of the rotatory advertising apparatus are the following:

50 As the compartments are separated from one another by opaque walls, the light illuminating any one of them cannot find access into any of the neighbouring compartments whereby the effect would be impaired. It is also impossible for an article accidentally becoming displaced and coming in contact with the inner surface of the appertaining mirror to check the rotatory motion of the drum as can occur in rotatory advertising apparatus having stationary mirrors in front of the rotatory compartments.

55 A very important feature resides in supporting the rotatory drum with its mirrors by grooved rollers forming at the same

time the members for transmitting motion from the motor to the drum. Apart from the simplicity of the construction, the particular advantage obtained is that the gearing in general and the motor in particular 70 is not impaired if a looker-on holds fast the drum so as to prevent it from continuing its movement for the time being, the motor, however, continuing to rotate. Finally, the contacts which are provided in convenient 75 position permit the change of the wiring connections for the lamps so that the succession of their switching on, as well as the number of lamps switched on at a time, can be varied as desired. 80

I claim:

1. A rotary advertising apparatus comprising, in combination, a vertical drum divided into compartments, semi-transparent mirrors forming the peripheral walls of 85 said compartments and adapted to serve as mirrors showing the surroundings of the drum when the compartments are dark but displaying the inner of the compartments when the latter are illuminated; a source of light alternately illuminating and darkening said compartments and means to rotate said drum.

2. A rotary advertising apparatus comprising, in combination, a vertical drum divided into compartments, semi-transparent mirrors forming the peripheral walls of 95 said compartments and adapted to serve as mirrors showing the surroundings of the drum when the compartments are dark but displaying the inner of the compartments when the latter are illuminated; a source of light alternately illuminating and darkening said compartments an annular member at 100 the lower end of said drum; a plurality of grooved rollers located below said annular member and being frictionally engaged by it; and means to rotate said rollers uniformly.

3. A rotary advertising apparatus comprising, in combination, a vertical drum divided into compartments, semi-transparent mirrors forming the peripheral walls of 110 said compartments and adapted to serve as mirrors showing the surroundings of the drum when the compartments are dark but displaying the inner of the compartments when the latter are illuminated; an electric source of light alternately illuminating and darkening said compartments contact-members provided at the lower end of said drum; stationary counter-contact members; conductive connections between the first-mentioned contact-members and said electric source of light; means to supply current to the counter-contact members, and means to rotate the said drum thereby alternately switching said source of light on and off. 120

4. A rotary advertising apparatus comprising, in combination, a vertical drum 130

divided into compartments, semi-transparent mirrors forming the peripheral walls of said compartments and adapted to serve as mirrors showing the surroundings of the drum when the compartments are dark but displaying the inner of the compartments when the latter are illuminated; an electric lamp in each compartment; an annular member at the lower end of said drum; a plurality of grooved rollers located below said annular member and being frictionally engaged by it; contact-members provided at the said annular member; stationary counter-contact members; conductive connections between the first-mentioned contact-members and said electric lamps; means to supply current to the counter-contact members, and means to rotate said rollers uniformly.

5 5. A rotary advertising apparatus comprising, in combination, a vertical drum

10

15

20

divided into compartments, semi-transparent mirrors forming the peripheral walls of said compartments and adapted to serve as mirrors showing the surroundings of the drum when the compartments are dark but 25 displaying the inner of the compartments when the latter are illuminated; an electric lamp in each compartment; a screen in front of each lamp; contact-members provided at the lower end of said drum; stationary counter-contact members, conductive connections 30 between the first-mentioned contact-members and said electric lamps; means to supply current to the counter-contact members, and means to rotate the said 35 drum thereby alternately switching said lamps on and off.

In testimony whereof I have signed my name to this specification.

CHRISTIAN GLEERUP-MÖLLER.
